UNITED STATES PATENT OFFICE

144,330

DESIGN FOR AN EMBROIDERED FABRIC

Anton Walter, New York, N. Y.

Application November 15, 1945, Serial No. 123,772

Term of patent 3½ years

(Cl. D92—1)

To all whom it may concern:

Be it known that I, Anton Walter, a citizen of the United States of America, residing in New York city, county of New York, and State of New York, have invented a new, original, and ornamental Design for an Embroidered Fabric, of which the following is a specification, reference being had to the accompanying drawing, forming part thereof, wherein,

The figure is a plan view of an embroidered fabric showing my new design; except for the continuous design pattern constituting the border of the fabric, the remainder, namely the spaced circular design patterns, repeat over the full length and width of the fabric.

I claim:

The ornamental design for an embroidered fabric, substantially as shown and described.

ANTON WALTER.
